BY MESNE ASSIGNMENTS, TO OTTO HEINEMAN PHONOGRAPH SUPPLY CO., INC., OF
NEW YORK, N. Y., A CORPORATION OF NEW YORK.

STOP MECHANISM FOR TALKING-MACHINES.

1,277,545.

Specification of Letters Patent. Patented Sept. 3, 1918.

Application filed April 8, 1915. Serial No. 20,050.

To all whom it may concern:

Be it known that we, PLINY CATUCCI and ANTHONY VASSELLI, citizens of the United States, and residents of the city of Newark, county of Essex, and State of New Jersey, have invented certain new and useful Improvements in Stop Mechanism for Talking-Machines, of which the following is a specification.

10 The invention relates to means for automatically starting and stopping the motor and the turn-table.

Numerous methods have been proposed for providing automatic stop mechanism for 15 disk talking machines, all of which, so far as we are aware, depend upon the travel of the tone arm across the face of the disk record for releasing some kind of trip device, said trip device actuating a brake. The 20 power of operating such brake is usually a spring set under tension upon the withdrawal of the brake from contact with the turn-table or tablet support. The motive power for actuating the trip device comes 25 directly from the grooves in the record itself. As the stylus of the sound box follows the groove, the sound box and the supporting tone arm are caused to travel in a horizontal plane across the face of the record, and if the trip mechanism works a trifle hard, the result is to crowd the stylus needle out of the groove and cause the same to 30 skip across from one groove to another, thereby producing a disagreeable grating 35 sound and frequent failure to release the trip.

One of the objects of our invention is to provide a release mechanism capable of 40 automatically starting the rotation of the motor and the turn-table, and to provide a stop mechanism, operating automatically to arrest the movement of the motor and turn-table.

Another object of our invention is to provide 45 means operable in conjunction with the turn-table spindle for automatically starting and stopping the motor and turn-table.

A further object of our invention is the 50 provision of means for automatically starting and stopping the motor and the turn-table, of the character described, simple in construction, thoroughly reliable and effi-

cient in its purpose, and inexpensive and economical to manufacture. 55

With these and other objects in view to be more fully set forth hereinafter, the invention consists in the novel construction, combination of elements, and arrangement of parts which will be exemplified in the construction hereinafter described in the specification and illustrated in the accompanying drawings considered together or separately. 60

The inventive idea involved is capable of 65 receiving a variety of mechanical expressions, one of which for the purpose of illustrating the invention, is shown in the accompanying drawings.

The invention will be first described in 70 connection with the accompanying drawings illustrating one embodiment of our invention, wherein similar reference characters are used to designate corresponding parts throughout the several views, and then 75 more specifically defined and indicated in the appended claims.

In our invention, as embodied in this application, we depend upon the motor spring 80 for power to actuate the starting and stopping mechanism as designed and built into the motor at the time of its original construction. The invention can also be applied to existing types of talking machines 85 by the utilization of a hollow turn-table spindle, as hereinafter described, and by affixing to such hollow spindle the invention herein. 90

In the embodiment of the invention forming part of this application, the driving mandrel is made tubular for a considerable portion of its length, and inside of said tubular portion we insert mechanism which, when in operative position will cause a brake arm to impinge upon the edge of the governor brake disk. The rotation of the spindle itself serves to set a brake upon some rotating part of the motor. 95

In the embodiment of the invention herein described and illustrated, we permit the 100 travel of the stylus needle across the face of the record to determine the point at which the motor is to be stopped, and for this purpose we provide an adjustable index arm, the point of which may be located at the 105 inner ring of the record groove before start-

ing the motor; after the motor is started this index will rotate with the tablet support or turn-table, and when the stylus needle has traversed the face of the record, the 6 point of the index, coming in contact with the stylus needle, or with some depending part of the sound box, will arrest the rotation of the index arm, while the continued rotation of the mandrel will operate the 10 mechanism to set the brake.

In the accompanying drawings forming a part of this specification—

Figure 1, is a plan view of the exposed portion of our improved stop mechanism, 15 the same comprising the adjustable contact arm; the position of the arm being shown as adjusted to the inner groove of the record tablet. The position of the sound box is also shown in dotted lines.

20 Fig. 2, is a side elevation of the detachable adjustable arm.

Fig. 3, is a side elevation of a portion of a motor showing our improvement in position for engagement with the edge of the 25 governor brake disk.

Fig. 4, is a vertical section through the mandrel.

Fig. 5, is a detached view partly in section of the operating mechanism.

30 Fig. 6, is a rectified view of the cam mechanism.

Similar letters of reference refer to like parts throughout the specification and drawings.

35 A mandrel 1, is drilled out for a portion of its length to form a tube, as shown in Fig. 4, at 2, to receive the operating mechanism. In this tubular portion is inserted a spindle 3. It will be noted that this spindle 40 reaches nearly to the bottom of the tubular portion of the mandrel 1. The spindle 3 is screw-threaded as at 4, and carries a collar 5, either rigidly secured to, or integral with said spindle 3; which serves the dual purpose of acting as a guide for the spindle within the tubular mandrel 1, and also as a shoulder against which a spring 6 may bear. Above the spring 6, and surrounding 45 the spindle 3, is a sleeve 7, the upper end of which is provided with a spiral cam 8 and shoulder 9. Adjacent to the shoulder 9, a short section 10 of the cam, is cut away at right angles to the axis of the sleeve 7. The spindle 3 is provided with a cylindrical portion 11, from which a downwardly projecting toe 12 extends parallel to the axis of the spindle. Next above the cylindrical portion 11, is a squared portion 13, and finally a knurled handle 14. When the parts of the 50 spindle are assembled, as shown in Fig. 5, the spring 6 is under considerable compression between the lower end of the sleeve 7, and the rigid collar 5. It will be noted now, that if the sleeve 7 is rotated around 55 the spindle 3, the cam 8 on the sleeve will

cause said sleeve to slide up and down on the spindle 3, or what amounts to the same thing, if the sleeve 7 is held rigid against rotation or longitudinal movement, the rotation of the spindle 3, within the sleeve 7, will cause said spindle to rise as the toe 12 rides up on the cam 8 to the horizontal part 10, the shoulder 9, of course, limiting the further rotation of the spindle. On the other hand, assuming the position of the spindle with the projection 12 upon the horizontal part 10 of the cam 8, after the spindle is rotated in the opposite direction with the sleeve held rigid, the spindle will be given a longitudinal motion downward. The sleeve 7 is held rigid within the tubular spindle 1, by means of a small set screw 15.

The lower end of the tubular part of the mandrel 1, is provided with a lateral opening or slot 16. Surrounding the mandrel, 60 adjacent to this slot 16, is a collar 17, upon the upper face of which is rigidly secured, by means of a screw 18, an arm 19, which projects through a slot 16 and is provided upon its inner end with a screw-threaded aperture to receive the threaded end 4 of the spindle 3. The lower end of the mandrel 1 is provided with pinion teeth 20, by which the mandrel is driven through a driving gear 21. The mandrel is further provided with a worm wheel 22 which engages a worm 23 upon a governor shaft 24. The governor is of the usual brake disk type and the shaft 24 is mounted in bearings 25 and 26, which are carried by the frame 27 of the motor. A sliding brake disk 28 operates in the usual manner by being drawn back and forth on the shaft 24, as the governor balls 29 fly outwardly through centrifugal force.

Mounted upon any convenient part of the motor frame, as for example, a vertical standard 30, is a resilient brake spring 31 which extends adjacent to the mandrel 1, and just beneath the collar 17 with the forward end of said spring in position to engage the edge of a governor brake disk 28, when the collar 17 is in its lowermost position. The normal biasing of the brake spring 31, however, is away from the edge 32 of the brake disk 28, so as to permit the governor shaft 24 to rotate freely. The detachable cross arm, shown in Figs. 1 and 2, consists of a central hub 32 having a squared aperture therein, so that it may be located over the squared portion 13 of the spindle 3. Rigidly secured to the hub 32 is an arm 34 which carries at one end a counter-balance 35, and its opposite end has secured thereto, an adjustable index arm 36, said index arm being secured to the arm 34 by means of a knurled thumb piece 37. When in position upon the upper end of the spindle 3, this detachable cross arm is in position just above the face of the record 38, which rotates in 130

the direction of the arrow 39. The adjustable arm 36 may now be adjusted so that its point 40 will be immediately adjacent to the inner record groove of the tablet 38. When the tablet 38 is in position, and the adjustable arm 36 is properly adjusted in position adjacent to the inner record groove, the operator then grasps the handle 14, turns it clock-wise to cause the projection 12 to ride up the cam 8 of the sleeve 7, and rest upon the horizontal plane against the shoulder 9; this operation, it will be noted, will cause the collar 17 to rise into the dotted line position shown in Fig. 3, thereby releasing the spring 31 from the edge of the disk 28. The governor is therefore free and the motor can begin to run. The tone arm 41 and sound box 42 may then be adjusted to playing position, and of course, the record groove will cause the sound box to traverse the face of the record 38 until such time as the stylus 43 begins to traverse the inner record groove. It will be understood that the detachable arm 34, and the adjustable arm 36, are rotating with the mandrel 1 and record 38.

When the stylus 43 reaches the inner record groove, the point 40 of the arm 36 will engage the stylus and therefore arrest the rotation of the arm 34, but since this arm 34 is connected to the spindle 3, the continued rotation of the mandrel 1 and sleeve 7, will cause the projection 12 to ride from the high portion of the cam 8 to the lower portion of the same, and thereby produce a vertical downward movement of the spindle 3, carrying with it the collar 17 under the impulse of the spring 6, but the downward movement of the collar 17 will carry with it the brake spring 31, causing its outer end to bear with considerable pressure upon the edge of the brake disk 28, and thereby immediately arresting the rotation of the governor and consequently stopping the motor. The threading of the spindle 4 into the apertured arm 19, serves the additional purpose of giving the collar 17 a slightly greater motion along the mandrel 7, than would be produced by the cam 8 alone; but since the cam 8 must be limited, slightly less than the circumference of the sleeve 7, and all of the parts must be contained in the interior of the mandrel 1, the easy working of the parts requires that the cam 8 should be a spiral of comparatively short pitch; otherwise the friction of the cam 12 against the cam 8 would make the parts work hard. By threading the lower ends of the spindle 3 at 4, we are enabled to produce the requisite added travel of the collar 17 so as to produce the requisite brake pressure upon the edge of the brake disk 28.

In order to limit the rotation of the index 36 about the end of the arm 34, we provide the index 36 with a rearward and upwardly bent projection 36' which will engage the

side of the arm 34 when the index is in substantial alinement with the arm 34. In replacing a record upon the top of a mandrel 1, it is only necessary to remove the arm 34 from the squared portion 13, and place the record upon the mandrel; thereafter the arm may be returned to its place and the index 36 adjusted as above described.

It might be thought that the contact of the point of the index 36, with the stylus 43, would injure such stylus needle; this is a matter of minor importance for it is the custom to discharge such needle upon the completion of the playing of a record and its injury need not be considered. In case, however, the stylus is a jewel, as diamond or sapphire the contact of the index with such stylus might be injurious. In that case, however, the sound box itself may be provided with a downward projection 95, upon its lower side, in position to engage the point of the index 36, and thus avoid any contact whatsoever of the index with the stylus.

It will thus be seen that by the structure 90 we are able to accomplish the automatic stopping of the motor upon the completion of the record by mechanism which applies frictional resistance to the rotation of some part of the motor itself, and such frictional resistance is set in operation upon the completion of the record by the motor itself. In other words, the continued rotation of the motor applies its own brake at a predetermined point in its operation.

In accordance with the provisions of the patent statute, we have described the principle of our invention together with the apparatus which we now consider to represent the best embodiment thereof, but we desire 105 it understood that our invention is not confined to the particular form of apparatus herein shown and described, the same being merely illustrative, and that the invention can be carried out in other ways without departing from the spirit of our invention, and, therefore, we claim broadly the right to employ all equivalent instrumentalities coming within the scope of the appended claims, and by means of which objects of 110 our invention are attained, and the new results accomplished, as herein set forth, as it is obvious that the particular embodiment herein shown and described is only one of many that can be employed to attain these 115 objects and accomplish these results.

We claim:

1. In a stop mechanism for talking machine motors, the combination of a record driving mandrel, a governor driven thereby; a balanced arm concentric with said mandrel, means for connecting said mandrel and said arm to cause the same to normally rotate together, an adjustable index arm carried by the balanced arm, and a friction 125

1. brake mechanism operating upon said governor and actuated by the stopping of said index arm to gradually stop the rotation of said mandrel.
2. In a stop mechanism for talking machines, the combination with the record driving mandrel and a governor driven thereby, of a balanced arm detachably connected with said mandrel to rotate therewith, an adjustable index arm carried by said balanced arm, and means associated with said arm and said governor, actuated by the stopping of the rotation of said index arm and acting through said mandrel, to gradually bring the same to a stop.
3. In a stop mechanism for talking machine motors, the combination with a rotating record driving mandrel and a governor driven thereby, brake mechanism, a balanced arm detachably connected to said mandrel to rotate therewith, an adjustable index mounted upon said balanced arm and capable of being adjusted toward and away from the center of rotation thereof, and mechanism connecting said balanced arm and said mandrel, said mechanism actuated by the contact of said index with an external object to stop the rotation of said balanced arm and simultaneously actuate said brake mechanism to stop the rotation of said governor and thereby stop said mandrel.
4. In a stop mechanism for talking machine motors, the combination with a record driving mandrel and a governor driven thereby, a balanced arm, means for connecting said arm to said driving mandrel to cause said arm to rotate with said mandrel, an index arm, a friction brake mechanism acting upon said governor, and means engaging the index arm for the stopping of the rotation of said index arm to operate said friction brake mechanism to stop said governor and thereby gradually stop the rotation of said mandrel.
5. In a stop mechanism for talking machine motors, the combination of a record driving mandrel and the regulating governor, gear mechanism between said mandrel and said governor for rotating said governor, a balanced cross arm, an adjustable index arm mounted on said cross arm to normally rotate with said mandrel and adapted to be engaged and stopped by the advancing sound-box stylus, and mechanism associated with said index arm and operating through the rotation of said mandrel to stop the rotation of said governor and mandrel upon the stopping of the rotation of said index arm by the sound box stylus.
6. In a stop mechanism for talking machines, the combination of a tubular record driving mandrel, and a regulating governor driven by said mandrel, an index arm to normally rotate with said mandrel, a spring brake mechanism mounted adjacent to said governor for contact with a part thereof, a spindle located within said tubular mandrel and connected with said arm, a collar mounted upon said mandrel for engagement with said spring brake, and means for reciprocating said spindle within said tubular mandrel to cause said collar to depress said spring brake into engagement with a part of said governor to stop the same when said index arm engages and is stopped by the sound-box stylus.
7. In a stop mechanism for talking machine motors, the combination with a governor having a brake disk thereon, a rotating mandrel having gear connections with said governor to drive the same, a spring brake rigidly mounted upon the motor frame in position for engagement with said brake disk, a reciprocating spindle within said tubular mandrel, an external collar on said mandrel connected to said spindle, an index arm detachably mounted upon said spindle to rotate therewith and with said mandrel, and means for reciprocating said spindle within said mandrel as and when said index arm is engaged and stopped by the sound-box stylus to cause said collar to depress said spring brake upon said brake disk and thereby stop the rotation of said governor.
8. In a stop mechanism for talking machines, the combination of a governor having a brake disk associated therewith, a record driving mandrel having gear connections with said governor to drive the same, said mandrel being tubular for a portion of its length, a reciprocating collar mounted upon said mandrel, a spring brake mounted upon the frame of said motor adjacent to said collar for engagement therewith and with said brake disk, a spindle within said tubular mandrel having a connection with said collar, and means for stopping the rotation of and for reciprocating said spindle to depress said collar upon said spring brake and thereby stop the rotation of said governor.
9. In a stop mechanism for talking machine motors, the combination of a motor having a brake disk mounted upon the shaft thereof, a record driving mandrel having gear connections with the shaft of said governor to drive the same, brake mechanism mounted upon the frame of said motor adjacent to said collar in position to bear upon said brake disk, and means within and normally rotating with said mandrel for depressing said collar against said brake mechanism to apply a braking pressure to said brake disk as and when the rotation of said means is stopped.
10. In a stop mechanism for talking machine motors, the combination of a governor having a brake disk mounted upon the shaft thereof, a record driving mandrel having

gear connections with the shaft of said governor to drive the same, a spring brake mounted upon the frame of said motor in position for engagement with said brake disk, and a reciprocating and normally rotating spindle within said mandrel for applying said spring brake to said brake disk whenever the rotation of said spindle is stopped.

10 11. In a stop mechanism for talking machines, the combination of a governor having a brake disk mounted upon the shaft thereof, a spring brake mounted upon the frame of the motor in position for engagement with said brake disk, a collar mounted to reciprocate upon said mandrel in position for engagement with said spring brake, a reciprocating spindle within said mandrel having an external connection with said collar, and means connected with said spindle for reciprocating the same to actuate said brake mechanism and thereby stop the motor upon a predetermined number of revolutions of said mandrel.

25 12. In a stop mechanism for talking machine motors, the combination of a tubular record driving mandrel and a ball governor, a brake disk mounted upon the shaft of said governor, gear connection between said mandrel and the shaft of said governor for rotating said governor, a spindle within said tubular mandrel, a collar mounted upon said mandrel and having a connection with said spindle, a spring brake mounted upon the frame of said motor adjacent to said collar and in position for engagement with said brake disk, an index arm detachably connected to said spindle to rotate therewith, an adjustable index connected to said index arm, and means connected with said spindle and mandrel whereby the stopping of the rotation of said index arm will cause said spindle to slide longitudinally within said tubular mandrel and through its connection with said collar depress the same and thereby set said spring brake against said brake disk.

13. In a stop mechanism for talking machines, the combination of a tubular record driving mandrel, a spindle within said tubular mandrel capable of independent partial rotation, a cam for moving the spindle longitudinally, a screw for supplementing the movement of the spindle, an arm detachably connected to the free end of said spindle, an index adjustably mounted upon the free end of said arm for adjustment to the inner ring of a record groove, a sound box having a depending projection thereon for engagement with the free end of said index when said sound box shall have traversed the face of the disk record, whereby such engagement will stop the rotation of said arms, brake mechanism connected with said spindle, and mechanism associated with said

spindle and mandrel for applying said brake mechanism to a rotating part of the motor upon the engagement of said index with the depending projection from said sound box.

70 14. In a stop mechanism for disk talking machine motors, the combination of a tubular record driving mandrel, means for rotating said mandrel, a spindle mounted for reciprocation therein and independent partial rotation, a cam for reciprocating the spindle, a screw for supplementing the movement of the spindle, an index arm having an adjustable index secured thereto, detachably mounted upon said spindle, 75 a brake mechanism associated with said spindle and with a rotating part of said motor, and a sound box having a depending projection in position for engagement with said index to stop the rotation of the same when said sound box shall have traversed the face of a disk record, whereby said stopping of the rotation of the index will cause a reciprocation of said spindle within said mandrel and the application of said brake mechanism to the rotating part of said motor.

80 15. A device of the character described, having a record driving mandrel, gear connections on said mandrel, a governor on a shaft having gearing meshing with the gear connections on the mandrel, a governor brake disk mounted upon the governor shaft, a spring brake in contact with means on the record driving mandrel in position for engagement with the governor brake 90 mechanism, a spindle on the record driving mandrel for operating the brake mechanism, and means for actuating the spindle.

16. A device of the character described, having a record driving mandrel, gear connections on said mandrel, a governor on a shaft having gearing meshing with the gear connections on the mandrel, a governor brake disk mounted upon the governor shaft, a spring brake in contact with means on the record driving mandrel in position for engagement with the governor brake disk, a spindle on the record driving mandrel for operating the brake mechanism, and means for reciprocating the spindle.

115 17. A device of the character described, having a tubular record driving mandrel, gear connections on said mandrel, a governor on a shaft having gearing meshing with the gear connections on the mandrel, a governor brake disk mounted upon the governor shaft, a spring brake in contact with reciprocating means on the record driving mandrel in position for engagement with the governor brake disk, a spindle within the record driving mandrel for operating the brake mechanism, and means for operating the spindle.

18. A device of the character described, having a record driving mandrel, gear con-

nections on said mandrel, a governor on a shaft having gearing meshing with the gear connections on the mandrel, a governor brake disk mounted upon the governor shaft, 5 a spring brake in contact with the record driving mandrel in position for engagement with the governor brake disk, a reciprocating and rotating spindle within said mandrel for operating said brake mechanism 10 and means for reciprocating and rotating the spindle.

19. A device of the character described having a record driving mandrel, gear connections on said mandrel, a governor on a 15 shaft having gearing meshing with the gear connections on the mandrel, a governor brake disk mounted upon the governor shaft, said mandrel being provided with a lengthwise tubular portion, reciprocating means 20 mounted upon said mandrel, a spring brake in contact with said reciprocating means and for engagement with the governor brake disk, a spindle within the tubular portion

of said mandrel, said spindle having connections with the reciprocating means for 25 actuating the brake mechanism, and means for reciprocating the spindle.

20. A device of the character described having a record driving mandrel, gear connections on said mandrel, a governor on a 30 shaft having gearing meshing with the gear connections on the mandrel, a governor brake disk mounted upon the governor shaft, said mandrel being provided with a longitudinal recess, means mounted upon said 35 mandrel, a spring brake in contact with said means and for engagement with the governor brake disk, a reciprocating spindle within the recess of said mandrel, said spindle having connections with the means on the mandrel for actuating the brake mechanism, and means for operating the spindle.

In testimony whereof we have hereunto set our hands this 6th day of April, 1915.

PLINY CATUCCI

ANTHONY VASSELLI.
